UNITED STATES PATENT OFFICE.

PORTER A. INLOW, OF MARTIN, TENNESSEE.

DESK ATTACHMENT.

1,059,299.

Specification of Letters Patent. Patented Apr. 15, 1913.

Application filed June 29, 1912. Serial No. 706,697.

To all whom it may concern:

Be it known that I, PORTER A. INLOW, a citizen of the United States, residing at Martin, in the county of Weakley and State of Tennessee, have invented new and useful Improvements in Desk Attachments, of which the following is a specification.

This invention relates to desk attachments and more particularly to typewriter or adding machine stands.

The object of the invention is to provide a simple and efficient device of this character which may be readily attached to any type of desk and in which the stand may be adjusted vertically so as to secure the proper height of the machine.

Further objects of this invention will appear as the following specific description is read in connection with the accompanying drawing, which forms a part of this application, and in which:

Figure 1 is a front elevation showing the typewriter or adding machine table thrown to inoperative position. Fig. 2 is a perspective view showing the stand arranged in operative position. Fig. 3 is a detail perspective view of the table support removed from the desk and standard.

Referring more particularly to the drawing, 1 represents a desk which may be of any suitable type and forms no part of the

invention. Secured to one side of the desk are brackets 2 in which is journaled the vertical standard 3.

The table support comprises a substantially U-shaped frame 4 one end of which has secured thereto a collar 5 which surrounds the standard 3. The opposite end of the frame is continued downwardly and inwardly to connection with a collar 6 which also surrounds the standard 3. These collars are provided with set screws so that the frame 4 may be adjusted vertically on the standard when desired. Mounted upon the frame is a table 7 carrying an eye member 8 in one side thereof to be engaged by the hook 9 carried by the desk.

What is claimed is:

A desk supporting attachment for desks comprising bearing members, a standard journaled therein, a horizontally arranged U-shaped frame, vertically arranged collars adjustably mounted upon the standard, supporting legs formed integrally with the frame and connected to the collars and a table top secured upon the frame.

In testimony whereof I affix my signature in presence of two witnesses.

PORTER A. INLOW.

Witnesses:

GEO. E. FARMER,
J. MARTIN ADAMS.
